Invention

William Thurber

UNITED STATES PATENT OFFICE.

WILLIAM THURBER, OF OLEAN, NEW YORK.

IMPROVED MACHINE FOR FITTING PIPE AND OTHER BOXES.

Specification forming part of Letters Patent No. 40,779, dated December 1, 1863.

To all whom it may concern:

Be it known that I, WILLIAM THURBER, of Olean, in the county of Cattaraugus and State of New York, have invented certain new and useful improvements in machinery for fitting pipe and other boxes and cutting recesses in the hubs of wagons and other vehicles; and the following is a full, clear, and exact description of the same, reference being had to the accompanying drawings, making a part of this specification, in which—

Figure 1 represents a plan or top view of the machine. Fig. 2 shows a side view or vertical elevation. Fig. 3 shows a left-hand end view of the machine. Fig. 4 is a right-hand or front-end elevation.

My invention consists in the construction and arrangement of a skeleton face-plate or revolving chuck, the same being supported and held to rotate firmly in its position by series of self-adjusting friction-rollers, their edges being V-shaped, or they may be square, running in grooves in the periphery of the revolving chuck made to fit. Onto the face of this chuck carriage-wheels of various sizes may be clamped and secured by independent hooks or jaws at three or more points on the felloes, the center of the revolving chuck being open in the rear or through the driving pulley to admit of an arrangement for centering, boring, or cutting a recess in the end of the wagon-hub without changing sides or taking off the wheel from the face-plate.

My invention further consists in the movable or adjustable frame, to which the revolving skeleton face-plate and appendages are attached, together with a scale and indicator, to give the taper corresponding with the boxes being fitted, also the hinged girt or beam to support a sliding bar or shaft, on the end of which is fitted a reversible cone which may be brought to bear either in the center hole or on the outer edge of the end of the hub by the action of a crank-lever, rack and pinion, or by a weight and cord passing over a pulley, so that the hub or wheel can be centered instantly and secured in such a manner that the pipe-box or short boxes being let in and fitted, the periphery of the wheels will run perfectly true.

To enable others skilled in the art to make and use my improved machine, I will describe

it more fully, referring to the drawings, and to the letters of reference marked thereon.

Like letters indicate the part in all of the figures.

In labor-saving machinery, and especially for working in wood, it is desirable to combine as much as possible these elements—namely, simplicity of construction, durability, strength, and portability—an all for the purpose of accomplishing this I make for the base of my machine a frame of square timber, the side pieces, Z Z, being of sufficient length and the cross-pieces Y Y being framed in at the proper places, and of such length as to make the required width. This arrangement makes a light and strong foundation to support the working mechanism. Upon this base I place an upright frame of timber supported on each side by short sills or steps X X. These are secured together by a cross-timber, W, so as to be the same width as the side timbers, Z Z. In the center of the short sills X are framed vertical posts V V with a plate, U, across the top, in the center of which is a standard, T. To the cross-timber W there is framed at right angle an arm, S, which has a rule or scale of inches, s, starting in a line with the king-bolt u, which secures the upright frame to the base. There is another arm, R, attached by a link, r, to the king-bolt u. This arm will conform to the taper of the pipe-box placed therein, and by adjusting the frame to the angle found by this process a most perfect fit of the box can be made in the hub. To the end of the arm S is a link, t, connected to a hand-lever, v, for the purpose of easily adjusting the frame and work to the right angle. The frame is then fixed in place by the sliding stop x and thumb-nut y. On the right-hand or face slide of the vertical frame there is secured by bolts and nuts q q three curved arms of metal, A A A. On the ends of each are V-shaped friction-rollers B B, the curved arms being hung or pivoted on their centers or so balanced that the rollers B B will adjust themselves to the circle of the revolving skeleton face-plate or open chuck C, which has a groove, c c, turned into the edge of its periphery, so that it hangs upon the friction-rollers and is driven by a cross-belt, E, passing around a projecting rim or pulley, F, connecting with the pulley G on the main driving-shaft S, which has one

of its bearings in a box on the standard T. On the face of the revolving chuck C are three or more arms, D D D, projecting out far enough to receive and support the various size carriage-wheels. On each of the arms D are placed clamps of metal d d d, with thumb-screws e e e, for the purpose of fastening the wheel to the chuck C by clamping the felloes.

To facilitate the centering and adjusting the carriage-wheel to the skeleton face-plate so that the rim will run true when the boxes are fitted in, I have invented and perfected an arrangement of mechanism which performs that thing to a certainty, as well as other important functions, which are described as follows: To one of the upright posts V, I hinge a broad beam, Q, in such a manner that it can open and swing round so as to leave the chuck C free from all obstructions on the rear side, convenient for trying in the common wagon-boxes when they are to be fitted in the outer end of the hub. The beam Q, when closed, is fastened by a belt and screw-nut, p. A metal lathe-head, H, is fitted on about the middle of the beam Q, which has a sliding bar, h, working in a line with the center of the revolving skeleton chuck C, the slide h being operated by a crank-pinion, j, and rack i on the outer end of the slide h, which has on its square part an adjustable stop, k, to which a cord, l, is fastened, which passes over a pulley, n, to a suspended weight, m. By this arrangement the slide and fixtures are kept gently pressing against the end of the hub while it is being centered and secured to the chuck. On the end of the sliding bar h, I have fitted a hollow cone, I. When desirable to center the wheel by the outer edge of the hub, the concave side of the cone is placed toward the hub; but when centering from the hole in the hub the cone I will be reversed, the point outward to enter the hole, the clamps d d d being brought to the rim of the wheel. It is very speedily secured in the position to bore and perfectly fit the box and cut or turn in the recess for washer or linch pin in the outer end of the hub. A recess of any desirable depth may be cut by putting a lip or a proper-shaped bit, o, on the end of the sliding bar h. The head H may be moved from the center by sliding it on the beam Q and set, there being a mortise, f, through the beam, with a bolt and thumb-nut for that purpose.

The arrangement of mechanism for holding the tool or cutter to bore or turn for fitting in the box does not differ materially in its construction or operation from the common slide-rest engine-lathe. However, in this connection I will give it a more full description.

On the face side of the skeleton-chuck, on the right-hand end of the frame platform, I place two timbers, K K, supported on four posts, L L L L, which are framed into the cross-pieces Y Y. On the top of the timbers K K I place ways or guides N N of metal, into which a slide, O, is fitted, there being secured on the top of the slide an adjustable tool-holder, N, which, being pivoted toward the other end, so that it may be varied laterally and secured at any desired point by a regulating thumb-screw, o', the shank of the cutter P is fitted into and held in the sockets p p. The tool may be brought in contact with the hub, and fed in by hand with a crank rack and pinion; or it will operate automatically by sliding the open nut a', connecting the slide o with the screw b', the same being operated by the cross-belt E', which communicates power and motion from the pulley F' on the main shaft g to the pulley H' on the screw-shaft b' at the right-hand end of the machine, above which is the forked standard W, to support and form the bearing of one end of the main driving-shaft g.

The great advantages of my invention are that pipe or other boxes can be perfectly fitted into the hubs of wagon or carriage wheels, (no matter how tough or cross-grained the wood may be,) so that the rim of the wheels will run true and track with each other; and, furthermore, the boxes can be fitted into a set of four wheels in less time than a single box can be fitted into one wheel by any other known process.

Having thus fully described my invention, what I claim as new, and desire to secure by Letters Patent, is—

1. The skeleton face-plate or open revolving chuck supported in its place by self-adjusting friction-rollers on balanced arms, the rollers fitted to run in a groove in the periphery of the chuck, to which carriage-wheels are attached for the purpose of fitting in pipe or other boxes constructed and operated in the manner herein specified.

2. The adjustable frame, to which the face-plate is attached, in combination with the lever-arm, rule-scale, and indicator, to give the hole in the hub the exact taper of the pipe-box being fitted.

3. The arrangement of the hinged beam Q, the sliding bar h, and cutter g, the regulating-stop k, and weight m, with the reversible cone I for centering the wheel, in the manner as described, for the purposes herein set forth.

WILLIAM THURBER.
